UNITED STATES PATENT OFFICE

JOHN CESSNA SHARP, OF CHATTANOOGA, TENNESSEE, ASSIGNOR TO NATIONAL OIL LUBRICATING COMPANY, OF CHATTANOOGA, TENNESSEE, A CORPORATION OF DELAWARE

LUBRICATOR

Application filed May 9, 1924. Serial No. 711,985.

This invention provides a most effective lubricating means characterized by extreme simplicity of construction and extraordinary economy in the use of oil, and which is capable of a wide application but is more particularly intended for use in situations wherein the oiler may be most conveniently positioned below the part to be oiled. The lubrication of overhead shafting whose hangers or 10 bearings are suspended from ceilings form a leading example of a use in which the lubricating means forming this invention has an advantage additional to those derived from its great simplicity and efficiency.

15 Bearing boxes for overhead shafting are sometimes of the ring oiler type—which embodies a reservoir from which the oil is fed by rings—and sometimes of a type merely provided with holes through which oil is squirted 20 at suitable frequent intervals by an attendant. This invention calls for no special construction of bearing box, being applicable to either of the foregoing types, or to any other type it 25 being understood, however, that when it is applied to the ring oiler type the rings are unnecessary and should be removed.

In the accompanying drawings, one embodiment of the invention is shown but changes in the details may be made, without departing 30 from the spirit of the invention or the scope of appended claims. In said drawings, wherein like characters of reference denote corresponding parts in the several views:—

Fig. 1 is a view, partly in section, of a part 35 of an overhead shaft and an ordinary type of bearing therefor, provided with the lubricating means of the present invention arranged at opposite ends of said bearing,

Fig. 2 is a view, on a larger scale than 40 Fig. 1, showing a part of the shaft and bearing box and a part of the lubricating means, wholly in section: and also showing a guard for the container,

Fig. 3 is a view showing the invention applied to a bearing of the type having a reservoir, the reservoir, however, performing no reservoir function when this lubricating means is applied thereto.

A designates a shaft to be oiled and B 50 designates one very ordinary form of bear-

ing through which the shaft extends. C is the Babbitt lining of said box.

The oiler constituting the present invention comprises a suitable oil container, as D, and a rigid suspending unit for said container, 55 which unit includes an oil filtering and feeding element F tightly encased in a rigid hollow body member, as the sleeve E for example. The oil filtering and feeding element F is a wooden plug, preferably having a straight 60 grain extending lengthwise thereof and preliminarily treated to remove pitch, tar, resin, moisture, etc., therefrom, and thereby to open the pores for the free passage of oil there- 65 through, the treatment preferably consisting in the boiling of the feeder in oil, at a tem- perature sufficiently high to remove the resin, etc., but below the point at which the feeder would be scorched or charred. The wood is then preferably but not necessarily filled with 70 a suitable lubricating oil, as one having the characteristics of that in connection with the feeding of which it is to be used.

In the illustrated embodiment of the invention the oil filtering and feeding element 75 F protrudes at both of its ends from the sleeve E and the latter is formed at its upper end to be secured to the bearing B and has its lower end provided with means by which the connection between the sleeve and the oil con- 80 tainer D will be sufficiently loose to permit said container freely to swing or turn with relation to the sleeve.

The illustrated oil container D is an ordinary transparent glass bottle having an externally threaded neck and provided with a cap D' having a threaded flange d' to engage the threads on the neck of the container. When a container of said, or any similar, construction is employed, the lower end of the 85 sleeve E is preferably formed with a shoulder, as the flange e, to engage the underside of the cap D', said cap having an opening d' through which the sleeve extends loosely. Below the flange e the sleeve E is shown as 90 formed with a polygonal head e' to be engaged by a wrench for convenience in screwing the threaded upper end e'' of the sleeve into a hole formed in the bearing B to receive the same.

In applying this lubricator to a bearing, the container suspending and oil feeding unit, with the cap D' resting on the flange e, but with the container detached, is first secured 5 to the bearing, with the upper protruding end of the plug F in a position to be in contact with the surface of the shaft to be lubricated. In practice, the sleeve E is usually screwed into the lower half of the bearing 10 at a time when the latter is free from the upper half of the bearing and from the shaft and the upper end of the element F is then cut down flush with the contiguous surface of the Babbitt lining C, through which it 15 extends, it being understood, of course, that in the assembling of the sleeve E and element F the protrusion of the latter from the upper end of the sleeve is of such extent as to permit a portion thereof to be removed in 20 fitting the container suspending and oil feeding unit to the bearing and shaft, i. e. to assure proper holding engagement of the sleeve E with the bearing and proper contact of the element F with the shaft. When 25 the said unit and the lower half of the bearing have been thus assembled, said half of the bearing is then secured to the upper half of the bearing, about the shaft, and thereafter the container D with a supply of oil therein 30 is secured to the cap D', and the oil will then be taken up by the wooden plug F and fed by the latter continuously and slowly to the shaft, in amount automatically regulated by the speed of rotation of the shaft, and never 35 in any excessive amount. Whenever the oil in the container D is to be renewed, it is necessary only to unscrew said container from the cap D', refill it, and rescrew it to said cap.

The simplicity of the construction is 40 apparent. It will be noted that there is an entire absence of springs or other means exerting pressure on the oil feeding element to hold it against the part to be lubricated. There are only a few parts in the entire 45 structure and these parts are of simple nature. The efficiency is remarkable. Several of them have given continuous service for nine months on shafts running eight hours a day, and throughout that entire time consumed only about one-half inch of oil in a two ounce container, about two inches in diameter at its widest part. They have been used for lubricating shafts running from 300 R. P. M. to 2500 R. P. M. and on shafts from one- 50 inch to three-inches in diameters with remarkable savings in the use of oil in all cases. Five weeks' use on a shaft running 2500 R. P. M. showed no noticeable depletion of the oil in the container, which was the size 55 hereinbefore mentioned, namely, a two ounce bottle about two inches in diameter at its widest part. In no case, has there been any deterioration in the bearings or shafts, and it has been established that in every case the 60 proper amount of lubricant, without either

excess on the one hand or under supply on the other, has been fed to the parts to be lubricated.

The loose suspension of the container D from the sleeve E insures that the vibrations to which the bearing is subjected will not be communicated to the container, and hence the danger of slackening of the container cap due to such vibrations, is avoided. Its capability of swinging also protects the container against liability of breakage and of breaking away from its suspending unit when accidentally subjected to a blow. If desired, the container may be further protected by a guard, the one here shown comprising a cage, H, of suitable construction, having spring fingers h which by pressing upon the cap D' also tend to prevent slackening of the cap. 70 75 80

As the replenishing of the oil calls only for the detaching of the container D from the cap D', leaving the latter in place on the sleeve E and said sleeve with the feeder plug F assembled in position with relation to the bearing and shaft, it is apparent that the attendant may quickly and conveniently renew the supply of oil, and with no danger of waste or spillage of oil upon products in course of manufacture adjacent the containers, which particularly in certain installations, is of great importance, an instance being textile manufacture in which the dripage of oil upon the textile being manufactured is disastrous. There is slight, if any possibility of dripage from the wooden plug F when the container is off, as the plug never takes up more oil than it can give off, but if there should be any excess of oil in the plug at the moment the container is removed this can readily be wiped off and no excess on the surface will thereafter develop while the container is removed. 85 90 95 100 105

The use of a wood plug F as the oil feeding element makes it practicable to arrange the container at any distance below the bearing from one inch up to several feet, the plug efficiently conducting the oil slowly but surely to the shaft to be lubricated, regardless of its length. With further reference to the plug, it may be noted that it should be made of a close grained wood, such as pine, and that the fit between it and the sleeve E should be sufficiently close not only to form a rigid unit of these two elements, preventing their accidental separation at any time, but also to compress the plug, thereby assuring a slow feed of the oil, the preliminary treatment to which the plug is subjected assuring that the feed be continuous and that the oil will be pure, the plug acting not only to feed but to filter the oil. This plug and the process of making it has been illustrated, described and claimed in a separate application for Letters Patent filed by me December 11, 1922, Serial No. 606,332. 110 115 120 125 130

Having thus described the invention, what I believe to be new and desire to secure by Letters Patent, is:—

1. An oil feeding means comprising an oil container having a detachable cap, and an oil-feeding unit extending through the cap and having a suspending connection therewith, said unit including a hollow suspending member and a wooden plug tightly fitted in said member and protruding therefrom.

2. In an oil feeding means, an oil-feeding and oil-container suspending unit having a hollow member and a wooden plug tightly fitted in said member and protruding therefrom, an oil container, and means providing a loose connection between the reservoir and unit.

3. An oil feeding means, comprising an oil-container having a detachable cap, and an oil-feeding and container-suspending unit having a hollow member which extends loosely through the cap and is provided with means to co-operate with the cap in suspending the container, said unit also having a wooden plug tightly fitted in said member and protruding therefrom.

4. In an oil feeding means, an oil container having a cap threadedly connected thereto, and an oil feeding unit comprising a tubular member and a wooden plug tightly fitted in said member, said member extending loosely through the cap and having a shoulder below the cap to co-operate with the cap in suspending the container.

5. In an oil feeding means, an oil container having a movable cap, an oil feeding unit comprising a tubular member and a wooden plug tightly fitted in said member, said unit having means to engage the cap and suspend said container, and a guard having resilient means to engage said cap and hold it in place.

6. In an oil feeding means, an oil container having a movable cap, an oil feeding unit comprising a tubular member and a wooden plug tightly fitted in said member, said unit extending loosely through said cap and having a shoulder which co-operates with the cap in suspending said container from said unit, and a guard connected to said unit having resilient means outside the container to bear upon said cap.

7. An oil feeding unit for lubricators comprising a suspending tubular member and an oil feeding wooden plug tightly fitted in said member and protruding therefrom and for carrying the oil upwardly to the bearing.

8. An oil feeding unit for lubricators comprising a tubular suspending member and an oil feeding plug formed of a close-grained wood treated to remove resinous and similar ingredients therefrom, said member and plug being tightly fitted to each other.

9. An oil feeding unit for lubricators comprising a tubular suspending member and an oil feeding plug formed of a close-grained wood treated to remove resinous and similar ingredients therefrom, said plug being fitted in said member with sufficient tightness to be under compression. 70

10. An oil feeding unit for lubricators comprising a tubular member and a wooden plug tightly fitted in said tubular member 75 and protruding therefrom, the tubular member having a shoulder near one end to suspend an oil container and being threaded at its other end to engage a bearing and having below said shoulder a polygonal section for convenience in screwing it into the bearing. 80

11. An oil feeding means comprising an oil container and a rigid oil-feeding and container-suspending unit formed separate 85 from the container and including a rigid hollow body member provided with means to secure it immovably to a bearing and with means from which the container may be suspended, and a wooden oil-feeding and filtering plug tightly fitted in and immovable with relation to said member, and protruding therefrom. 90

12. An oil feeding and container-suspending unit comprising a rigid tubular body member one of whose end portions is formed to be secured to the bearing to be lubricated and the other of whose end portions has means to suspend the oil container, and a rigid oil feeding and filtering plug tightly fitted in said body member and protruding therefrom, said plug formed of wood from which natural pore filling substances have been removed to thereby increase its capillarity. 100 105

In testimony whereof I affix my signature.
JOHN CESSNA SHARP.
